UNITED STATES PATENT OFFICE

WILLIAM D. HAMBY, OF MORTON, PENNSYLVANIA

BOXING MASK

Application filed August 6, 1931. Serial No. 555,522.

This invention relates to an improved boxing mask which is so constructed as to be most effective in providing protection for vital parts of the face and head while conforming readily to the features. The padding employed is of such form and so disposed as to protect the ears, head, cheeks and jaw and pad sections are spaced so as to leave openings therebetween for the nose and eyes and at the same time protect those vital parts. More particularly, the improved mask includes in combination with the head and ear pads separate cheek pads which are movable relatively and so related to the nose and eyes as to permit free breathing and free vision without liability of injury.

In the improved mask in addition to the features enumerated provision is made for adjusting it to the head conveniently, such means being light in weight.

The invention will be described in detail in connection with the embodiment shown in the accompanying drawings, in which:

Figure 1 is a view in front elevation of the improved mask.

Figure 2 is a view in section taken on the plane indicated by the line 2-2 of Figure 1 and looking in the direction of the arrows.

The mask is made of any suitable pliable material such as leather which will not injure the skin where engaged with it and at the same time will enable the separate portions of the padding to conform nicely to the contour of the head and face. Any suitable sort of padding is placed within the leather. As shown in Figure 1 the front structure of the mask comprises a unitary head piece *a* which extends across the front of the forehead and is curved as at *a'* to conform generally to the contour of the eyes. A central section *a*² extends down between the eye openings to afford ample protection to the nose. At the sides of the mask are ample ear pads *b* which are preferably oval in shape so as to overlie the ears without interfering with hearing. The lower part of the mask is made essentially of two separate pads *c* which are secured at their rear edges to the body of the mask as indicated at *c'* by stitching. The connection of the pads *c* with the body of

the mask is such that the pads are hinged and are freely movable. The lower edges *c*² of the pads extend down to the jaw line so as to protect it, and the upper edges *c*³ may be curved to conform generally to the curvature *a'* of the body of the mask in proximity to the eyes. The inner edges *c*⁴ of the pad *c* have secured thereto a flexible strip *d* which may be of leather which is also secured to the depending nose pad *a*². The strip *d* has a central opening *d'* therein opposite the nose so as to permit free breathing.

At the rear, the mask is provided with securing strips *e* through which pass a lacing *f* to permit the mask to be adjusted to the head of the wearer. Cross straps *g* pass over the crown of the head to support the mask. These securing devices are light in weight and convenient in use. A chin strap *h* is secured to the lower edges of the main body *a* of the mask to retain it in place.

When the mask is applied to the head and the lacing *f* taken up it will be found that the ear pads *b* overlie the ears in proper relation thereto, the form and sides of the pads being such as to adapt them to the heads of different sizes. The main body of the mask *a* will extend over the forehead and down over the temples to the line of the jaw. The separate pads *c* will embrace the cheeks snugly and conform to the contour of the face. The relation of these pads to the main body of the mask is such as to protect effectively the eyes and nose while leaving clear vision and free breathing.

Changes in details of construction and form may be made without departing from the invention.

What I claim is:

1. A boxing mask having a body portion extending over the forehead, downwardly over the nose, and down over the sides of the head, open ear pads connected to the body portion at opposite sides thereof, and separate cheek pads secured flexibly to the body portion adjacent the downwardly extending portion for the nose and to the ear pads and spaced from the body portion to form openings for the eyes.
2. A boxing mask having a body portion

extending over the forehead and down over opposite sides of the head, a nose pad extending downwardly from the pad across the forehead, the body portion being formed with curved edges conforming generally to the eyes, a flexible strip secured to the nose pad and having an opening therein opposite the nose of the wearer, separate cheek pads to which said strip is secured, said cheek pads being also directly secured at their free edges to the main body of the mask and open ear pads connected to the body portion at opposite sides thereof and to the cheek pads.

This specification signed this 19th day of
15 June A. D. 1931.
